UNITED STATES PATENT OFFICE.

WARREN D. LANGIELL, OF MALDEN, MASSACHUSETTS.

SADDLE FOR HORSES.

1,182,021.

Specification of Letters Patent.

Patented May 9, 1916.

Application filed December 7, 1915. Serial No. 65,600.

To all whom it may concern:

Be it known that I, WARREN D. LANGIELL, a citizen of the United States, residing at Malden, in the county of Middlesex and 5 State of Massachusetts, have invented a new and useful Saddle for Horses, of which the following is a specification.

The object of my invention is to provide a saddle for horses, which is designed to be 10 used either as express or carriage harness and is sanitary and waterproof, in that the same eliminates the use of the cloth covered and padded linings found on the under-side of the ordinary saddle, as well as the 15 separate felt pads commonly used with said saddles, and humane because the same is designed with special and rigid non-yielding supporting members which are embedded within the saddle and positioned 20 therewith to seat the same upon the hollows of the animal and to provide the saddle with an arched throat which exposes and clears the backbone of the horse; said supporting members serving also as guards for 25 preventing the projecting-studs and screws of the saddle fittings (*i. e.* terret-studs, pad-screws, seat and hook bolts) which are secured to and protrude within the saddle, from rubbing or otherwise bearing down 30 upon the back or backbone of the horse,—it being a known fact that the ordinary types of saddles are designed with cushioned linings on the undersides thereof which usually settle and become flat, when the projecting-studs within the saddles are 35 permitted to bear down upon the back and backbone of the horse and cause sores and wounds to appear which are painful to the animal and hard to cure, and when the common types of hair or felt pads are 40 resorted to and are used for overcoming that situation, they too soon flatten down and settle and cause the parts directly below the studs to become hard and compressed, and 45 thus permit the pressure of the studs to have their full effect upon the back of the horse. It is also a known fact that both the cushioned linings of the ordinary types of saddles and the separate felt or hair pads 50 used with them, are heating and susceptible to dampness, readily absorbing whatever moisture comes into contact therewith, either from weather conditions, as rain or snow, or from body conditions, as perspiration, causing the saddle to grow very uncomfortable when once the linings or pads 55

become wet, the same requiring considerable time to dry in, thereby creating an unsanitary condition, as well as resulting in the destruction of the saddle through allowing 60 the material of the same to become rotted or rusty, as the case may be.

Still another object is to provide a comfortable wearing saddle, embodying the improved features above referred to, which 65 is simple in construction, inexpensive to manufacture, and absolutely durable and reliable.

To these as well as other ends, my invention consists of the novel features of construction, combination and arrangement of parts described in the following specification and especially pointed out in the subjoined claims.

Referring to the accompanying two sheets 75 of drawings—Figure 1, represents a perspective view of a saddle embodying my invention. Fig. 2, represents an enlarged cross-section taken transversely through the throat of the saddle. Fig. 3, represents a 80 perspective view of a part of a common form of metallic tree used within a saddle. Fig. 4, represents a plan view of the leather tree piece which fits within the tree shown in Fig. 3. Fig. 5, represents a plan view of 85 the back-band-loop guide piece. Fig. 6, represents a plan view of a part of the outer skirts of the saddle, showing the slot through which the back-band-loop is inserted within 90 the saddle. Fig. 7, represents an enlarged longitudinal section taken through the saddle, showing the construction of the same and the application of the supporting pad-box therewith. Fig. 8, represents a sectional view taken on line 8—8 in Fig. 7. 95 Fig. 9, represents a perspective view of the leather supporting pad-box used in the saddle, the same being drawn inverted for showing the preferred construction thereof. Fig. 10, represents a pattern for the supporting box when the same is made up of 100 leather, sheet metal or other suitable material.

Like numerals refer to like parts throughout the several views of the drawing.

The numeral 1 in its entirety represents an ordinary metallic tree, which is used within the saddle, having the seat and throat portion 2 beyond which projects the right and left extensions 3 and 4, respectively, and the back-strap-loop 5. The tree extensions 3 and 4 at the extreme ends of 110

the same are provided with the offset webs 6. The tree extensions are also provided with the terret openings 7, the rivet holes 8, and the pad-screw recesses 9. The seat 5 of the tree is provided with the seat-screw recess 10, the hook-screw-recess 11, and the hook-locking-lug recess 12.

13 are the leather outer skirts of the saddle which butt together at the top 14 10 over the throat 15 of the saddle.

16 represents the ordinary ornamental seat, usually provided on the top of the saddle and covered with the leather covering 17.

15 18 is the check-rein hook which bears on the seat 16 and is provided with the stud 19 and the locking-lug 20 which protrudes within the saddle, as shown in Fig. 2,—the stud 19 being provided with the nut 21 20 which secures the hook to the saddle.

22 are the ordinary terrets which seat upon the skirts 13 and are provided with the studs 23 which protrude within the saddle and engage with the terret-nuts 24, which nuts 24 are riveted and secured to the middle piece 25 of the leather tree piece 26, which piece has the outer strips 27, the outer side edges of said tree-piece 26 reaching the outer edges of the skirts 13 and 30 similar in shape thereto.

28 is the back-band-loop-guide piece (leather) which is provided with the slot 29, within which the lower strip 30 of the back-band-loop 31 fits, which back-band-loop is provided with the pad-screw 32 and the terret-hole 33, said pad-screw 32 engaging with the pad-screw-nut 34 which is set within the recess 9 of the web 6 of the tree extension.

40 35 represents the leather foundation piece for the supporting member 36, which is preferably made wedge-shaped and of leather, being securely stitched to the foundation piece 35 on three sides, with the 45 fourth side 37 preferably left open so that the pad may be stuffed with hair, or other suitable padding material 38 when desired and then stitched down with the stitches 39, as shown in Fig. 9; the outer side edges of

50 said foundation piece 35 also reaching the outer edges of the saddle skirts and similar in shape thereto, as in the case of said tree-piece 26, for affording a means of securing and stitching said tree-piece and said foundation piece together with the outer skirt, 55 as shown in Figs. 1 and 8.

40 represents an ordinary rivet which grips the skirt 13, the back-band-loop-guide-piece 28, the tree piece 26, the foundation 60 piece 35, and the supporting member 36 together.

41 is a protector-washer and throat strip which is preferably made of leather of sufficient thickness, and is provided with the 65 holes 42 and 43 within which the check-rein-

hook-stud 19 and the seat-stud 44 fit, respectively,—the hook-nut 21 and the seat-nut 45 bottoming on the protector-strip 41, without permitting the studs to protrude beyond the strip 41, as shown in Figs. 2 73 and 7.

46 represents a padding of any suitable material, such as hair, felt, et cetera, which may continue across the arch of the throat at 47, as shown in Fig. 7, or not, as shown 75 in Fig. 2.

48 is preferably a leather covering, such as collar leather or other suitable material, which is preferably waterproof, non-moisture absorbing, but yielding, and incloses 80 the underside of the saddle and forms part of the lining therefor.

49 is the inner skirt, or lower lining piece (leather) which continues down to the extreme end 50 of the saddle, where the billet-loop 51, preferably of the D type 52, is secured to the saddle, as shown in Fig. 1; the outer edges of said inner skirts reaching the edges of the outer skirts and similar in shape thereto, for permitting the same to be stitched and secured thereto at the edges as shown.

53 represents a leather chape, with which is associated the back-band 54, the ends 55 of which are preferably stitched together 95 to properly engage with the shaft-tug which is secured thereto.

Having thus described the parts of my invention in detail, it will be first observed 100 that I use the standard types of saddle trees, seats, check-rein-hooks, terrets, and back-band-loops, which compose practically all of the fittings found associated with the common types of saddles, and that secondly, 105 by inspection of the drawings, especially Figs. 1, 2 and 8, it will be observed that the particular construction and design of the saddle permits the use of the same as an express or carriage harness. The design of 110 the saddle incidentally provides for a skirt in which the edges of the same are required to overhang and project beyond the lining and the padding of the supporting members on the underside of the saddle, and thereby sheds the water coming in contact therewith and thus eliminates the possibility of water working into the interior of the saddle, as is found to be the case with the 115 construction of the ordinary types of saddles which usually finishes off with projecting beads around the edges of the skirt and offers the water on the surface of the skirt, an opportunity to easily enter within the saddle proper, thereby subjecting the material within the saddle to the possibility of becoming wet, which ultimately rots and 120 rusts the same and takes the life out of the cushioning members of the saddle causing them to set, sag, and flatten, when the me- 125

130

tallic projecting members within the saddle are no longer protected against bearing down upon the body of the horse which causes great discomfort and pain, and often 5 results in incapacitating the animal from work.

It must also be observed that the general appearance of my type of saddle resembles the ordinary saddles on the market 10 and is especially applicable for all classes of express work. The construction of the same is very simple and may be manufactured by machinery as well as by hand.

It may be observed that while I speak of 15 constructing the pad boxes and tree-pieces of leather, I do not wish to be limited against using other suitable material in its stead.

It will be observed that the supporting 20 pad-boxes may be made of any suitable shaped cross-section longitudinally,—the wedge-shape, as shown in Fig. 7, being the most preferable, however. The supporting members, when set in working position with 25 the saddle, prevent any possibility of the projecting-studs of the terret and pad-screws, or the webs of the tree of the saddle, from interfering with the body of the animal in any possible manner. The depth 30 of the supporting members may be made to suit, the object being to sufficiently raise the arch of the throat of the saddle so that the same will at all times free the backbone of the animal, and as a special prevention in 35 cases where the backbone of the animal is high and comes into contact with the throat of the saddle. The special washer-strip 41 serves to positively prevent the studs of the check-rein-hook or the seat from protruding 40 beyond the same and coming into direct contact with the animal,—it being understood that in the ordinary types of saddles, the throats of the same, as soon as the cushion linings flatten, bear down directly 45 upon the back of the animal and invariably result in creating wounds, since no provision is made for preventing the studs of the check-rein-hook or the seat from rubbing upon and interfering with the backbone of 50 the animal. The design of the saddle permits the use of a leather lining, as against the ordinary cloth linings used on common types of saddles. The leather lining, while not absolutely waterproof unless specially 55 treated therefor, is naturally more or less non-moisture-absorbing, and thus may be greatly depended upon for preventing water from working within the interior of the saddle, as is the case with the ordinary 60 cloth lining which is absorbing and slow to dry. The design of the saddle, with the edges of the skirts projecting beyond the supporting members, has every tendency to shed the water coming in contact with the 65 saddle, as from rain or snow, instead of of-

ferring the same an opportunity to work its way within the saddle, as is the case with the ordinary types of saddles on the market,—it being understood that the projections on the skirt and the parts of the 70 saddle which are stitched to the same on the underside thereof, form practically a right angle with the lining on the sides of the supporting members, as suggested by the dotted lines shown in Fig. 8, said figure 75 showing the construction of the same exaggerated and therefore the projections of the skirts and the parts secured thereto, do not form the right angle with the lining of the saddle as above suggested, the dotted 80 lines indicating more nearly the true condition of the parts when finally secured together.

It may be further observed that the saddle affords a compact arrangement which 85 permits the rigid securing of every part therewith, producing an inexpensive saddle which is durable, absolutely sanitary, and positively humane in every respect.

It may further be understood that my 90 type of saddle may be employed for all classes of work to equal advantage, the same being adapted for light as well as heavy service.

While the preferred embodiments of my 95 invention have been described in detail, it will be understood that I do not wish to be limited to the particular construction set forth, since various changes in the form, material, proportions, and arrangement of 100 parts and in the details of construction may be resorted to without departing from the spirit and scope of the invention, or destroying any of the advantages contained in the same, heretofore described and defined in 105 the subjoined claims.

What I claim is—

1. In combination with a rigid saddle-tree and saddle-skirts; tree-pieces provided with terret-nuts secured thereto and adapted to interlock with the saddle-tree on either side thereof; hollow wedge-shaped pad-boxes provided with extension supporting strips; and cushioning means inclosing said wedge-shaped pad boxes,—the sides of said 110 tree-pieces and said pad-box extension strips being shaped similar to that of said saddle-skirts and adapted to be stitched and secured thereto, substantially as shown.

2. In combination with a rigid metallic 115 saddle-tree and leather saddle-skirts; leather tree-pieces provided with terret-nuts secured thereto and adapted to interlock with the saddle-tree on both sides thereof and to be rigidly secured thereto; hollow leather 120 wedge-shaped pad-boxes provided with extension base-plates; and leather covered cushioning means inclosing said pad-boxes,—the side edges of said tree-pieces and said extension-base-plates of said pad-boxes be- 125 130

ing shaped similar to that of the saddle-skirts and adapted to be stitched and secured thereto, substantially as shown.

3. In combination with a rigid metallic saddle-tree and saddle-skirts; leather back-band-loop guide pieces, provided with slots adapted to receive the back-band-loops of the saddle; leather tree-pieces provided with terret-nuts secured thereto and adapted to interlock with the saddle-tree on both sides thereof and to be rigidly secured thereto; hollow leather wedge-shaped pad-boxes provided with extension - base - plates; and leather-covered cushioning means inclosing said pad-boxes,—the side edges of said tree-pieces and said extension-base-plates of said pad-boxes being shaped similar to that of the saddle-skirts and adapted to be stitched and secured thereto, substantially as shown.
- 20 4. In combination with a rigid saddle-tree and saddle skirts; tree-pieces provided with terret-nuts secured thereto and adapted to interlock with the saddle-tree on either side thereof; hollow wedge-shaped pad-boxes provided with extension supporting strips; cushioning means inclosing said wedge-

shaped pad-boxes; and inner lining-skirts,—the said tree-pieces, pad-boxes and inner lining-skirts being shaped on the sides thereof similar to said first mentioned saddle 30 skirts and stitched and secured thereto, substantially as shown.

- 35 5. In combination with a rigid metallic saddle-tree and saddle-skirts; leather back-band-loop guide pieces, provided with slots adapted to receive the back-band-loops of the saddle; leather tree-pieces provided with terret-nuts secured thereto and adapted to interlock with the saddle tree on both sides thereof and to be rigidly secured thereto; 40 hollow leather wedge-shaped pad-boxes provided with extension base-plates; leather covered cushioning means inclosing said pad - boxes; and inner - lining - skirts;—the said tree-pieces, pad-boxes, and inner-lining-skirts being shaped on the sides thereof similar to said first mentioned saddle-skirts and stitched and secured thereto, substantially as shown.

45 WARREN D. LANGIELL.
